UNITED STATES PATENT OFFICE

136,308

DESIGN FOR A MEDAL OR SIMILAR ARTICLE

Arthur F. Huebner, Bay City, Mich.

Application November 20, 1942, Serial No. 108,828

Term of patent 3½ years

To all whom it may concern:

Be it known that I, Arthur F. Huebner, a citizen of the United States, residing at Bay City, in the county of Bay and State of Michigan, have invented a new, original, and ornamental Design for a Medal or Similar Article, of which the following is a specification, reference being had to the accompanying drawing, forming a part thereof.

In the drawing:

Fig. 1 is a face view of the medal showing my new design.

Fig. 2 is a face view of the opposite side of the medal.

Fig. 3 is a vertical sectional view.

I claim:

The ornamental design for a medal or similar article, as shown.

ARTHUR F. HUEBNER.
